SULPHURIC-ACID MANUFACTURE.

1,415,353.

Specification of Letters Patent. Patented May 9, 1922.

Application filed May 9, 1919. Serial No. 295,943.

To all whom it may concern:

Be it known that I, GEORGE F. HURT, a citizen of the United States, residing at Atlanta, in the county of Fulton and State of Georgia, have invented certain new and useful Improvements in Sulphuric-Acid Manufacture, of which the following is a specification, reference being had therein to the accompanying drawing.

This invention relates to sulphuric acid manufacture and more particularly involves the novel method or system of manufacturing sulphuric acid, and an apparatus capable of carrying out such method or system. The invention comprises an improvement in that part of the method or apparatus which utilizes sulfur dioxid gas, that is following the actual burning of the brimstone or other sulfur containing material, or feeding of sulfur dioxid from other source. More particularly this invention relates to the action within or intermediate the Glover tower and the first of the lead chambers, or these and the converter, and the interaction and intermediate connection as between these portions of the plant. The main objects are to improve efficiency, increase output and render more uniform and reliable the operation and production of a given plant.

To the attainment of these objects and advantages the present invention consists in the novel method, system and apparatus and the novel features of procedure, operation, combination, arrangement, and details thereof herein illustrated, described or claimed.

Fig. 1 shows more or less diagrammatically a side elevation of an entire sulphuric acid manufacturing plant, in which the principles of the present invention are embodied or can be practiced.

Fig. 2 is a similar view on an enlarged scale of the particular portion of the apparatus to which the present improvement especially refers.

Fig. 3 is a top plan view of part of the apparatus shown in Fig. 2.

Referring first to the general features of the plant shown in Fig. 1, the operations commence with the burning of the sulfur, which is preferably performed in a suitable burner A, to yield sulfur dioxid, which, however, may be supplied in any desired manner. From the burner the gases in an intensely

hot condition, and comprising principally sulfur dioxid, pass through a flue B into the lower end of the so-called Glover tower C, above which is a nitrogen supplying vessel D. After treatment in the Glover tower the gases pass therefrom successively through the lead chambers or acid chambers E, F, G, etc., and thence into the base of the so-called Gay-Lussac tower I, the function of which is well understood and forms no part of the present invention. In the passage or flue E' between the Glover tower and the first chamber is shown an exhaust E'. Pipes F' constitute exits for the first chamber E, conducting the gases onward to the second chamber F.

A converter J is shown of the general type known as the Pratt converter, this having a flue or pipe J' leading to it from the first chamber E, and one or more compartments or cones J², within which liquid may be sprayed, as usual in such converters. From the outlet at the top of the converter J passes pipe J³, carrying the gases back to recirculate. Heretofore the passage J³, has been extended, as indicated in dotted lines at J⁴, so as to conduct the gases to the exhaust E, and thence to the first chamber. In the present invention, however, the very important improvement is introduced in eliminating the extension J⁴, and instead continuing the exit pipe J³ from the converter by a pipe or passage J⁵ leading into the Glover tower C. The arrangements, functions, operations and importance of this feature will be elucidated hereinafter. In part the improvement may be availed of by carrying the exit flue J' back to the Glover tower, without first passing through a converter, for example, when the plant embodies no converter.

The Glover tower, as indicated in Fig. 2, may be considered as internally divided into or consisting of zones of operation or function, and, as will be explained, these zones C', C², C³ and C⁴ may be considered as four in number, the first being the topmost and the last the lowermost interior portion of the tower.

There are various well known details of construction and operation of the Glover tower and other illustrated elements which need not be described, but will be understood, these elements being shown only

conventionally herein. The construction and operation of the vessel D, which furnishes the desired nitrogen compounds, and the source of such compounds, will be understood and need no especial description.

The sulfurous gases passing into the Glover tower usually include sulfur dioxid, sulfur trioxid, and impurities. The sulfur trioxid is small in amount and immediately 10 combines with steam to form sulphuric acid in the Glover tower, and therefore offers no particular problem and will be hereinafter ignored. The sulfur dioxid is required to be supplied with water 15 and oxygen, the apparent reaction being $\text{SO}_2 + \text{H}_2\text{O} + \text{O}$ equals H_2SO_4 , but, as is well known, an intermediate product, nitrosyl sulphuric acid, $\text{SO}_2\text{OH}\cdot\text{ONO}$, hereinafter referred to as nitrosyl acid, must be produced 20 by the aid of nitrogen oxids or nitric acid present or supplied through the vessel D, and the sulphuric acid condenses therefrom in the presence of water (steam) and oxygen.

The best conditions for formation of 25 nitrosyl acid from sulfur dioxid (SO_2) and nitrous anhydride (N_2O_3) are low temperature, and large oxygen excess in the presence of sulphuric acid. These conditions exist in the upper part of the Glover tower, 30 where the cooled descending acid meets the rising sulfur dioxid, nitrogen oxids and oxygen, also in the upper part of the chambers close to the water sprays therein and in the spray cones of the converter. In each 35 of these apparatuses and wherever sulphuric acid condenses from nitrosyl acid, nitrous oxid (N_2O) is released. It combines with oxygen to form nitrous anhydride, which later is recombined into nitrosyl acid, more 40 particularly in the Glover tower, the first chamber and the converter. The nitrogen compounds thus pass through a cycle, being used over and over, and finally recovered in the Gay-Lussac tower and usually returned 45 to the vessel D over the Glover tower. As the output of any plant depends on the rapidity and extent of formation of nitrosyl acid, it is important to maintain the most favorable conditions for such formation 50 throughout the plant. Therefore in the Glover tower should be maintained ample excess of oxygen, a full supply of sulfur dioxid and a full supply of cool acid; steam being sufficiently supplied by the concentrating effect at the lower part of the tower. Low temperature at the upper part of the tower is also important. Substantially the same statement applies to the conditions in the first chamber and the converter, in each 55 of which active circulation should be maintained to ensure thorough mixing and intimate contact.

The conversion of nitrosyl into sulphuric acid occurs in the Glover tower, the chambers and the converter, the requisite condi-

tions being that the nitrosyl acid be not too strong, that there shall be sufficiently high temperature and ample supplies of sulfur dioxid and water with a small excess of oxygen. These conditions prevail in the lower 70 part of the Glover tower, but not at the bottom, and in the portion of the chamber removed from the walls and sprays, and within the entire central or packed space of the converter. 75

I have thus found that within the packed space of the Glover tower, there are virtually four different zones of action.

In the topmost zone C', which may be termed the absorption zone, nitrosyl acid is 80 being continually formed by the absorption of nitric oxid, (N_2O_2 , formed in the second zone from N_2O released and rising from the third zone), together with the sulphuric dioxid and oxygen entering from the burners, and steam from the bottom zone. The reaction is not a direct one, as the nitric oxid is selectively first converted into nitrous anhydrid and nitrous acid. The action, of course, is progressive, there being 90 no definite lines of demarcation between the zones. The supply of nitrogen compounds is maintained at the desired low temperature in the absorptive zone by reason of the cool incoming agent descending from the 95 vessel D above, this being, for example, sulphuric acid from the Gay-Lussac tower containing the recovered nitrogen oxids, together with the nitrogen compounds added at the vessel D. The best results require 100 that the products passing through the Glover tower be cooled to substantially a temperature slightly over 100° C., that being the best temperature for the gases passing 105 to the chambers.

The nitrosyl acid thus formed is a heavy vapor, which is absorbed by downcoming acid, and descends, finding its way down through the tower through the second to the third zone. It will be understood, of course, 110 that the exit E' from the top zone is constantly carrying off gaseous products to the first chamber, but each portion of nitrogen within the Glover tower repeats its cycle of reactions numerous times before finally escaping, and passing with the uncombined sulfur dioxid, steam and oxygen to the chambers. 115

The second zone C², which is substantially neutral or indifferent, is not a region of chief 120 activity of any of the processes referred to. In fact, the reduction of this zone is of no harm, but on the contrary its reduction by the enlargement of the adjoining zones, if that can be accomplished, tends to greater 125 efficiency. Thus, by properly controlling the materials fed in at the top, the first zone can be maintained of maximum depth and volume and sufficiently cool throughout for the purposes of its reactions. The third zone, 130

likewise, as has been explained, can be beneficially expanded, although there should remain a transition zone between the first and third zones. The second zone is not wholly functionless as before stated, the rising N_2O from the third zone is here converted into N_2O_3 .

The third zone C³ is the denitration zone. Here the nitrosyl acid becomes denitrated, thus forming sulphuric acid and releasing nitrous acid, which rises, as before stated, to the first zone. This reaction, as before explained, depends in part upon the high temperature of the third zone. It cannot commence until reaching a sufficiently hot strata. The rising hot sulfur dioxid, oxygen and the steam driven off in the fourth zone react with the downcoming nitrosyl acid, the resulting liquid, sulphuric acid, descending, and the gaseous products rising to the upper zones. The importance will now be observed of extremely high temperature in the gases supplied to the Glover tower. Increased temperature of the gases results in quicker denitration and therefore more effective production in the Glover tower of sulphuric acid.

The fourth or bottom zone C⁴ is the concentration zone, and functions to drive off from the descending sulphuric acid the water contained therein, which rises in the form of steam and is utilized in the third and first zones and in the first chamber, as before explained. The acid drawn off at the base of the Glover tower is extremely concentrated, and is of great value commercially, for direct use in many chemical processes, and is available for use in the recovery processes in the Gay-Lussac tower.

The gases, including sulfur dioxid, which pass along from the Glover tower to the first chamber, are thoroughly mixed and permitted to thoroughly combine in the latter, going through a cycle similar to that already explained. The condensed sulphuric acid is collected in the water pan at the bottom, while the nitrogen oxids rise and at the cooler parts of the chamber recombine into nitrosyl acid, resulting in further condensation of sulphuric acid. The carrying on of these cycles and the mixing of the gases in the first chamber are enhanced by maintaining the circulation therein such as indicated in Fig. 3. The incoming gases are seen to pass along the center and reversely at the sides, forming two long eddies, which carry the gases alternately to and from the water cooled parts of the chamber.

The reactions in the first chamber are rendered more active and thorough by the recirculation of the gases through the use of the converter. After an amount of sulphuric acid has been condensed out in the converter, the gases are sometimes caused to pass back and enter again the first chamber,

along with the comparatively fresh gases from the Glover tower. The second passage of the gases gives increased travel and circulation in the first chamber, and therefore an increased number of cycles of formation of nitrosyl acid and its splitting up into sulphuric acid and nitrous oxid. In the converter a relatively large amount of sulphuric acid is condensed, owing to the thorough saturation of the entering gases, the substantial internal heat of the converter and the thorough mixing effected therein in the presence of a large area of packing surfaces, with which the nitrosyl acid contacts.

The spent gases, that is, having lowest SO_2 content, finally pass out from the first chamber by the exit pipes F', F', after having completed their travel, so that the maximum production is secured before the gases are carried to the second chamber. In that and subsequent chambers the condensation of sulphuric acid is much reduced, because of the exhaustion of the necessary ingredients and the lowered temperature, but the action continues throughout the successive chambers until substantially all the sulfur dioxid is used. The first chamber yields a considerably larger amount of acid than any of the subsequent ones, especially as its length and space is usually considerably larger, and the acid making elements are richer, and the circulation more active; so that in the later chambers the conversion of sulfur dioxid to nitrosyl acid and the latter to sulphuric acid is for the purpose of effecting the highest possible recovery of sulphuric acid from the sulfur burned.

Referring again to the converter, this is fed by the gases from the extreme end of the first chamber, which on entering the converter are saturated by the sprays, being cooled to the critical temperature for formation of nitrosyl acid, and containing the proper components for that reaction. The nitrosyl acid thus formed enters the body of the converter, which, being not only quartz packed, but brick lined, holds considerable heat and serves to reheat the gases, the nitrosyl acid taking up oxygen. Nitrous oxid is thus released while the sulphuric acid runs down as a liquid and is drained away.

As before stated, heretofore the nitrous oxid from the converter, also the inert nitrogen and the residues of sulfur dioxid, oxygen and water vapor have been carried from the top of the converter to the main flue leading from the Glover tower, where the same mix with the fresh gases from the Glover tower; so that they are used over and over again in the production of nitrosyl and then sulphuric acid, and finally are conducted to the front end of the first chamber, so that part of the nitrogen elements are recirculated and used again and again.

In any given part of the plant the effi-

ciency of sulphuric acid production depends on three considerations, the richness of the gases, including vapors, in the necessary ingredients, proper temperature conditions and thorough mixing. The conditions in the Glover tower are different from the chambers, the cycle of production being much more rapid. This is partly because the gases are much richer, there being unlimited quantities of oxygen and water vapor and plenty of nitrous oxid yielded by the denitration in the third zone. Also because of the great absorptive capacity of the first zone afforded by the cooled acid, which is put down into the top end of the Glover tower, giving the best conditions for the absorption by the incoming acid of the nitrogen oxids. Also because of the greater temperature range in the Glover tower, one extreme being cool enough to produce nitrosyl sulphuric acid and the other hot enough to condense sulphuric acid therefrom.

According to the present invention, as before stated, the nitrogen oxids and the residual-gases from the top of the converter are carried back, not merely to the first chamber, but to the Glover tower and caused to enter the upper part thereof. Preferably this recirculation inlet leads into the second or neutral zone, as indicated in Fig. 2. The important results of this improvement require the following explanation, which will be understood to those skilled in the art after consideration of the conditions hereinbefore already explained.

The residual-nitrogen oxids from the converter can work to much greater effectiveness in the absorption zone of the Glover tower than in the first chamber, because in the Glover tower the cycle of reactions is more active and rapid. In other words, the oxids are set into operation where their work is most effective.

Moreover, the gases from the converter are relatively cool, and their action therefore in the first zone of the Glover tower is to increase the cooling effect, and thereby enlarge the depth and space of the first zone at the expense of the second or neutral zone. This increases the absorptive capacity of the Glover tower, correspondingly increasing the production of nitrosyl, and therefore of sulphuric acid. This, as already stated, is of great advantage, especially as the acid produced in the Glover tower is of the greatest value.

A resultant advantage is as follows. The increased utilization of sulfur dioxide in the Glover tower would at first sight seem to reduce the quantity or percentage thereof which passes on to the first chamber, the converter, etc. The capacity, however, of these elements of the plant remains as high as before. We may, therefore, increase the rate of supply of burner gases, or other SO_2

containing gases, to the Glover tower. The larger quantity of sulfur dioxide passing to the tower ensures that the residues passing on to the chambers possess adequate sulfur dioxide content. The exit of the Glover tower is shown provided with a damper C^5 regulating the passage of gases through the flue E' , and the increased flow of gases into the Glover tower is attained by opening such damper. 75

It will be perceived from these conditions that, owing to the increased acid producing reactions in the Glover tower, and also to the increased rate of supply of sulfur dioxide thereto, it is possible to put down 80 into the top of the Glover tower a greater quantity of the cool and weak acid with nitrogen content. This again tends to increase the space of the first or absorption zone, giving better efficiency. Owing to the 85 same cause, more water vapor is driven off in the third zone and carried upward and on to the first chamber. A more evenly balanced gas mixture is thus furnished to the front end of the first chamber, as regards the percentages of the necessary components of nitrosyl acid. This gives more effective reactions within the first chamber. 90

The net results, therefore, of the described improvement include materially increased 95 production of acid in the Glover tower, and increased production as well in the first chamber, both of these valuable results being secured without increased consumption of nitrating material. The acid production 100 in the second and subsequent chambers, it should be stated, continues substantially unchanged. Therefore, with a given plant and with a given nitre consumption, that is, given in amount, and therefore reduced in 105 percentage to the acid production, a materially greater sulphuric acid production is attainable, and the operations are excellently reliable in their efficiency and uniformity.

It will thus be seen that I have described 110 an example of a process or system and apparatus for the manufacture of sulphuric acid embodying the principles of the present invention. Since various matters of procedure, combination, arrangement, construction, detail and other features may be variously modified without departing from the underlying principles of the invention, there is no intention to limit the invention to such features except in so far as set forth in the 115 appended claims.

What is claimed is:

1. The method of sulphuric acid manufacture comprising passing gases from the Glover tower through the chamber, thence 125 through a converter and returning the same from the converter to the upper part of the Glover tower.
2. The method of sulphuric acid manufacture comprising passing gases from the 130

Glover tower through a chamber and thence back into an intermediate part of the Glover tower for recirculation.

3. Apparatus for sulphuric acid manufacture, comprising a Glover tower, a chamber, passages from the Glover tower to the chamber, and passages from said chamber

leading to a point above the base of the Glover tower for recirculation into the Glover tower and chamber. ¹⁰

In testimony whereof, I have affixed my signature hereto.

GEORGE F. HURT.
